DESIGN FOR A BOTTLE

John L. Dunnock, Baltimore, Md., assignor to Swindell Brothers, Incorporated, Baltimore, Md.

Application February 2, 1939, Serial No. 82,732

Term of patent 7 years

To all whom it may concern:

Be it known that I, John L. Dunnock, a citizen of the United States, residing at Baltimore city and State of Maryland, have invented a new, original, and ornamental Design for a Bottle of which the following is a specification, reference being had to the accompanying drawing, forming part thereof.

Figure 1 is a view in elevation of the front of the bottle, showing my new design,

Figure 2 is a view in elevation of the side of the bottle, and

Figure 3 is a plan view of the bottle.

I claim:

The ornamental design for a bottle, substantially as shown.

JOHN L. DUNNOCK.
